Holler, Washington, D. C.

Application February 8, 1945, Serial No. 576,830

12 Claims. (Cl. 102—65.2)

1

This invention relates to means for adapting hand grenades to launching from small arms such as the carbine and rifle.

It has for an object to enable the use in a launcher of grenades in which a hammer releasing lever is held against operation by a safety pin until the time of use, and wherein ordinarily, when about to be manually thrown, the pin is withdrawn and the lever held depressed by the hand in which the grenade is grasped for tossing.

It is particularly dangerous to vary the order of procedure in the arming and projecting of these explosives because of the extreme liability of accident with certainty of serious casualties in each instance, and therefore it is a paramount purpose of the invention to enable a procedure in which there is a minimum possibility of mistake by which a premature explosion of the grenade may be caused when launched from a firearm.

In a conventional hand grenade largely used the safety lever extends beside the spheroidal fragmentation body of the missile in the direction of its major axis, the minor circumference of the body being small enough to enable the missile to be readily grasped together with the safety lever in the hand of the user. This construction of hand grenade employs a striker at the extremity of the bouchon where the lever is attached. The striker is spring loaded to rotate on an axis transverse to the lever, from a position extending longitudinally inward beside the fuse. The striker moves radially at a substantial angle to the longitudinal axis of the grenade so that a substantial component of force is manifest acting toward the adjacent end of the grenade. The lever in this grenade is formed of a blank of thin sheet metal with a hooked end engaging a rounded fulcrum lip on the body of the fuse opposite the striker, and extends across the end of the grenade and then longitudinally inward beside the grenade at an oblique angle to the axis for a distance, lying over and against the striker to restrain firing movement of the latter.

The lever has ears at the sides beside the fuse apertured with the fuse body to receive the safety pin, by which the lever is secured against pivotal movement, and also against translatable movement in any direction.

While it is generally intended that the firing movement of the lever over a large part of its initial movement shall be pivotal, with the lip as the axis (after which the lever becomes freed and is thrown off by the striker), and while the

2

lever does so function initially, the extent of this pivotal movement before the lever is freed varies to some extent so that a freeing of the lever hook from the fulcrum lip occurs earlier under some conditions. This can occur in each device if not properly handled. While this fault is contributed to in a small degree by variations from standard proportions and shapes in manufacture, it is mainly possible because of the fact that the diagonal direction of the hook bill and longitudinal component of force of the striker causes the base portion of the lever beside the fuse body opposite the hook to move longitudinally of the grenade to some extent and away from the full engaged position with the lip of the fuse body. While the safety pin is engaged, and after withdrawal of the pin, the pressure exerted on the body of the lever by the grasp of the user tends to prevent such movement as might clear the hook from the fulcrum lip. But if loosely held, the diagonal direction of the hook, and a small amount of longitudinal and diagonal translatable movement of the lever which the clearances permit are sufficient to almost clear the lever, and a slight shock or impact of objects against the lever will cause it to become freed from the fulcrum lip and a premature firing is then certain to occur.

It is therefore an important aim of the invention to afford a simple launching holder in which the hand grenade may be set to be held unarmed after the safety pin is withdrawn, with complete security.

A further object is to present an attachable tail piece having the advantages enumerated, which may be engaged with conventional grenade launchers for effective functioning with the desired flight characteristics and satisfactory range values.

A very important attainment in view is to enable the adaptation of the hand grenade to launcher use with a minimum of complication in manufacture, with high economy of material by use of sheet metal stampings throughout.

A further purpose is to simplify the procedure in applying the adapter to the grenade so that the soldier may effect the assembly without special knowledge, training, or need of tools, but as an entirely manual operation. It is also an aim to enable the ready control of range of the grenade when launched from a rifle or carbine.

Also, it is sought to avoid impairment of the functioning of the fuse and explosive or the fragmentation of the body as customarily manifested.

Additional objects, advantages, and features of the invention reside in the construction, ar-

angement, combination of parts and methods of procedure in manufacture and in use, of the invention, as will appear or be understood from the following description and accompanying drawings wherein:

Figures 1 and 2 are full size side elevations of the invention, applied to a standard hand grenade, the safety pin being withdrawn in Fig. 2 and the clip indicated in course of setback movement (the tube omitted);

Figure 3 is a top view of Fig. 1;

Figure 4 is an elevation of the adapter alone;

Figures 5 and 6 are cross sections on lines 5 and 6 of Fig. 4;

Figure 7 is a view of finger 33 from the inner side with a part broken away and the clip sleeve in section;

Figures 8 and 9 are views on the lines 8 and 9 of Fig. 7;

Figure 10 is a fragmentary elevation of a launcher with my adapter applied;

Figure 11 is a section on the line 11—11 of Fig. 10, enlarged.

Referring to the drawings more particularly, there is illustrated a well known hand grenade comprising a cast iron shell body 10, oval in longitudinal section and circular in cross section, formed with one flat end 11 normal to the major axis, and at the other extremity a conical neck 12' to receive the fuse body 12 screwed thereto. The body 10 is externally formed with a series of circumscribing grooves 13 and longitudinal grooves 13' of wider spacing. These grooves are all substantially V-shaped in cross section, so that while comparatively wide at the extreme peripheral surfaces of the grenade the groove sides extend into the intersection of two sets of grooves so that they are nearly continuous across the bottoms of the intersections. Four-sided fragmentation blocks 14 are thus formed between the grooves. The fuse body has an outer planiform end face 15a normal to the longitudinal axis of the fuse, and a projecting lip 15 at one side having a rounded outer edge which is substantially semicylindrical with its axis parallel to the end face of the fuse and spaced laterally outward from the underlying side surface of the fuse. At the side of the body 12 opposite the lip there are cheek extensions 16, providing a recess in which the striker 17 is pivoted on a cross pin near the end of the fuse body and normally lying in the lower part of the recess spring loaded to swing laterally, longitudinally outward, and inwardly to engage the primer, as is well known in these devices. The safety lever 18 by which the striker is held in the normal position mentioned has a flanged flat top plate 19 which lies normally flat against the outer planiform end face of the fuse body and has a hook 20, of a form similar to that of the rounded edge of the lip 15 but of greater radius, and positioned so that it may fit loosely around and slightly spaced from the lip, especially at the extremity of the hook, where a maximum clearance is manifest, although the bill of the hook, due to its greater radius still extends under the lip to some extent when the lever is secured by the safety pin. The lever proper extends at an oblique angle from the plate 19, being curved inward in spaced relation to the grenade body 10, and has ears 21 at its base extending inwardly beside the cheeks 16, receiving therethrough the safety pin 22 on which the pull ring 23 is swivelled.

My adapter comprises a stabilizer or tail tube 25 of a diameter approximately the same as that

of the flat end of the grenade body and has a thin cylindrical tail fin 26 supported therearound by three spoke webs 27, the fin being of suitable diameter and length to act as a steering fin for the grenade when launched. A closing head piece 28 is fitted and welded within the forward end of the tube, and across this end a tie washer 29 is concentrically arranged, having four slots 30 therein at the perimeter of the tube normal to quadriradiates of the tube axis. Four longitudinally arranged leaf spring fingers 32 are engaged through respective slots 30, having their base ends 31 laid flat and secured against the side of the tube by riveting or otherwise. Three of these fingers 32 are of a length to extend slightly beyond the groove 13 at or nearest the middle of the shell body, while the fourth finger 33 is extended further so as to lie near the base of the neck 12'. The fingers are all extended divergently a distance above the washer 29, so as to receive freely the flat end 11 of the shell body against the washer 29, when the grenade is thrust within the fingers. All four fingers are curved inward at outer parts as far as the plane of the mid groove 13 of the grenade as the grenade sets against the washer. Here they are bent abruptly inward as at 34 at an angle greater than the angle formed by the sides of the grooves 13 with the extreme peripheral surfaces of the grenade body at the tops of the blocks 14, and then abruptly bent outward at 35 constituting claws with outer sides to extend at an acute angle to the extreme peripheral surface of the engaged grenade, forming wipers or cams 36. The angle formed by the major parts of the sides of the grooves 13 is something less than 90 degrees. The wiper parts 36 are extended a distance both radially and longitudinally greater than the corresponding measurements of the parts between the bends 34 and 35, and the three fingers 32 terminate at the extremities of the wipers 36. The material of the fourth finger is continued rectilinearly a distance at an oblique angle inward from the respective wiper 36, substantially as indicated in Figs. 4 and 1, forming a clip mounting arm 37. This arm extends such distance so as to lie closely under the lever 18 when a grenade is in engaged position in the adapter.

The end portion of the arm 37 is apertured near its extremity and an indentation or notch 38 pressed in the extremity of the arm, extending longitudinally inward a short distance toward the aperture. An arming clip retainer 39 is riveted at the extremity of the arm 37, being formed of strip spring material of 19 gauge stock of the same width as, but more brittle than the stock used in the fingers. Its riveted end portion is offset and apertured to receive a rivet 40 engaged in the aperture of the arm 37, securing the retainer to the arm 37. The end of the retainer is also indented at 41 so that the nib thus formed on the underside will engage and lock in the indentation 38 and hold the two rigidly in alignment.

At the extremity of the clip retainer a very narrow tongue 42 is formed extending inward sharply at right angles, and around the retainer there is a clip sleeve 43 of heavier gauge metal than the strip for the fingers, rectangular and oblong in cross section. The retainer 39 has a dimple forming a tip 44 projecting at the inner side toward the arm 37 so that when the retainer 39 and the lever 18 are engaged together through the sleeve the sleeve is pressed inward toward the lever, holding the sleeve against the outerside of the lever. The

tongue 42 projects from the body of the retainer to a length slightly more than the minor interior dimension of the clip sleeve, and the width of the strip stock is also greater than this minor dimension so that the clip sleeve can not be turned around the retainer sufficiently to aline the tongue with the major transverse dimension of the sleeve or to clear the end of the tongue from the end of the sleeve.

The major interior dimension of the sleeve 43 is much greater than the width of the fingers. The length of the sleeve is slightly less than the distance between the tip 44 and the tongue 42, and the material of which it is formed is sufficiently thick to involve a mass in the sleeve sufficient to cause it to overcome the friction between itself and the lever and retainer and to also break or bend the tongue 42, by setback when the adapter and grenade are propelled from a rifle or carbine equipped with conventional launcher as shown in Patents No. 2,339,285 and 2,335,299 to W. T. Moore. In assembly the clip sleeve is slipped on the retainer 39 before the latter is riveted to the arm 37 and then the retainer secured in place, the registered notch and indentation 38 and 40 keeping the parts 37 and 39 in alinement.

The interior dimension of the tube 25 is the same as that of the tail tubes of rifle grenades and the like. The launcher for such grenades consists, as is well known, of a tubular piston-like attachment for the end of the rifle, adapted to fit slidably in the tail tube 25, so that when a cartridge of suitable propellant explosive is then fired in the weapon the gases pass from the muzzle into the tail tube and are confined thereto by the launcher so as to propel the adapter and the grenade held therein over a distance much greater than the ranges possible by manual tossing.

In the use of this invention, the adapter being assembled as described, and the hand grenade being at hand to be engaged in the adapter, the latter is set erect upon some horizontal surface while the grenade, without special adjustment or modification, is positioned coaxially over the fingers of the adapter with the flat end 11 downward and the extremity of the safety lever 18 entered in the upper end of the clip sleeve, which is then resting on the tongue 42 and receives the lever end freely. The grenade is moved downwardly until it rests against the jaws parts 35 symmetrically, after which sufficient pressure is applied to cause the grenade surfaces to cam the fingers outwardly and enter therebetween until the jaws engage in the middle transverse circumferential groove 13, at which time the end 11 will be resting upon the washer 29. The jaws will then hold the grenade firmly in coaxial alinement with the tail tube. No special care is required to prevent the jaws from being alined with longitudinal grooves on the grenade shell, because the lower sides of all the grooves extend in to the intersections and afford proper engaging surfaces for the jaws in case a longitudinal groove wider at the top than the finger should be alined therewith.

Owing to the more acute angle of the wipers 36 to the grenade surfaces, positioning of the grenade is rendered much easier, and due to the greater angle of the inner parts 34 to the grenade parts, withdrawal of the grenade is quite difficult. In practice, for the grenade of the shape and size indicated, weighing approximately one and one-third pounds, the spring fingers are adapted to oppose a lateral pressure of in the neighborhood

of eight pounds each in maximum flexure in course of engagement on the grenade shell, and the tongue 42 is adapted to break at a pressure of fifteen pounds more or less, using a clip sleeve 5 having a weight of approximately .03 pound.

The grenade being fully engaged as described, the clip is moved upward around the dent 44, after which the safety pin 22 may be withdrawn by grasping and pulling the ring 23. This allows 10 a partial movement of the lever 18 by the outward thrust of the striker 17, to the position shown in Fig. 2, at which the lever is somewhat more firmly held against slippage in the clip and the pressure of the striker on the base of the lever draws the hook 20 more snugly around and 15 inwardly against the lip 15.

The adapter and engaged grenade now as a unit constitute a projectile ready for launching. A rifle or carbine having a launcher attached 20 and in readiness otherwise, a propellant cartridge is placed in the chamber of the arm and the adapter with the armed grenade engaged therewith is placed by sliding the tail sleeve 25 longitudinally inward on the launcher. The fire-arm being cocked and its butt set upon the ground, it is aimed and the trigger pulled to fire the propellant cartridge. The impulse thus imparted to the adapter and grenade moves them forward so rapidly that the inertia of the clip 25 sleeve overcomes the friction between the sleeve and the dent 44 and lever and causes it to move rearwardly on the two with such force that when 30 it strikes the tongue 42, the latter is broken and the sleeve clears the retainer and lever, permitting the latter to be thrown off by the striker in the manner well understood in such devices. The projectile has in the meantime been moving toward its target but the striker fires the percussion primer and ignites the fuse train before the 35 projectile has moved more than a few feet so that the bursting charge will be ignited effectively.

The tail fin in this instance is assembled in a 40 novel construction, consisting of three rectangular elongated blanks 45, with one end portion bent to substantially Z-shape, and one arm 46 greatly elongated and curved to the arc required. The short arms 47 of the blank are welded against the base end of the tube, with the long arms 46 45 all extending in the same direction, their extremities lapping and welded to the bases of the adjacent arms 46 which are inset to allow the extremities to set flush with the outer faces of the remainder of the curved parts 46 which now 50 form a complete cylinder. The connecting portions between the arms in each of the blanks thus 55 form spoke webs arranged radially as part of the fin.

Three spring fingers instead of four as shown 60 may be used on the adapter, in which case two would be short, corresponding to the ones 32, and the third would be as shown and described at 33.

As well known, the tubular piston fitting for 65 rifles and carbines which constitutes the common launcher, has a plurality of circumscribing grooves and alternate lands of uniform external diameter, the tail tube being of a diameter and length to fit closely and slidably around these lands to a full depth when the end of the piston engages the head 28. The latter position is proportionate to the maximum range desired with a standard propellant cartridge used in the rifle or carbine. In order to shorten the range, the 70 tail tube is engaged less than its full depth on 75

the launcher, and in order to check such application of the tube and prevent the tube from slipping further on to the launcher when the latter is elevated with the rifle for firing, we provide a positioning clip 50, which is a bifurcated spring with bowed arms 51 having divergent extremities 52 and an eye 53 at the junction of the arms. It is adapted to be presented with the ends 52 advanced endwise against the side of the launcher adjacent a groove or land, representing the range value required, and pushed transversely on to the launcher so as to embrace the latter and hold itself in place thereon. When the tail tube is applied to the launcher thereafter the clip 50 checks entrance of the piston at the proper depth to give the required range with a correlated propellant cartridge.

In practice the fingers are made of steel tempered to a degree to function satisfactorily as indicated, but the retainer 39, also of steel is tempered to a very brittle state so that the tongue 42 will be highly frangible and will break off rather than bend appreciably under the required setback force developed in the clip 43, a Rockwell "C" hardness of 60 to 64 being developed. In the spring fingers a Rockwell "C" hardness of 50 to 54 has been used.

Other modifications and expedients are also possible within the scope of the invention including substitution of materials and equivalents, mechanical or otherwise the present disclosure being purely exemplary although it represents meticulously the best embodiment of the invention as yet developed.

We claim:

1. A launcher adapter for a hand grenade having a safety lever, comprising a receptacle adapted to receive the grenade and its safety lever, said receptacle having a tail tube for engagement with a grenade launcher and a plurality of spring fingers extended longitudinally at one end of the tube and shaped to lie close beside and clasp the inserted grenade, a safety lever engaging clip attached to one of said fingers, a part movably mounted on the clip and adapted to engage the grenade safety lever to confine the same in a safe position, said part being movable relative to the clip to clear and thereby release the safety lever under set back upon propulsion of the receptacle with the grenade thereon, said part being responsive to the launching action of the grenade adapter launcher to become disengaged from the clip to release the lever.

2. A launcher adapter for hand grenades having a laterally movable safety lever, comprising a receptacle adapted to receive the grenade and its safety lever, a sleeve part slidably mounted on the receptacle and adapted to engage the safety lever to confine the same in a safe position, said sleeve part being movable on said receptacle to clear and thereby release the lever under setback on propulsion of the receptacle with the grenade advanced thereon, said receptacle having a tail tube for engagement with grenade launchers and a plurality of spring fingers extended longitudinally at one end of the tube and shaped to lie close beside and clasp an inserted grenade, said fingers having inturned claws, one of said fingers being extended beyond said claws thereon and having the sliding sleeve part thereon adapted to receive and disengage slidably the laterally movable safety lever of the inserted grenade, and responsive by setback to disengage the lever.

3. A launcher adapter for hand grenades having a laterally movable safety lever, comprising a receptacle adapted to receive the grenade and its safety lever, a sleeve part slidably mounted on the receptacle and adapted to engage the safety lever to confine the same in a safe position, said sleeve part being movable on said receptacle to clear and thereby release the lever under setback on propulsion of the receptacle with the grenade advanced thereon, said receptacle having a tail tube for engagement with grenade launchers and a plurality of spring fingers extended longitudinally at one end of the tube and shaped to lie close beside and clasp an inserted grenade, said fingers having inturned claws, one of said fingers being extended beyond said claws thereon and having the sliding sleeve part thereon adapted to receive and disengage slidably the laterally movable safety lever of the inserted grenade, and responsive by setback to disengage the lever, and a tongue on the finger projected across the path of the sleeve in disengaging movement, yieldable to a predetermined force.

4. An adapter for launching a hand grenade having a restrainable safety lever extending therebeside normally tending to move to operating position, comprising a cup-like grenade-receiving device having a tail tube and fins and spring grasping devices to engage and retain a grenade, and a safety lever holding means movable on one of said spring grasping devices and responsive to setback to release the lever.

5. A grenade launching mount for a hand grenade having a lateral longitudinal striker-restraining lever, comprising a finned, headed tail tube, forwardly and longitudinally extended symmetrically arranged grenade-grasping spring fingers on the forward end of the tube, a rearwardly extended offset clip support on the forward part of one finger and having a lateral tongue yieldable to a predetermined pressure, a sleeve longitudinally slidably thereon having an interior diameter less than the length of the tongue and adapted to receive slidably the safety lever of a grenade within the fingers, said sleeve having a mass capable of manifesting pressure in excess of said predetermined pressure under setback when the mount and engaged grenade are fired from a launcher.

6. In a launcher adapted for a fragmentation grenade having a circular shell body with a plurality of circumscribing grooves therein, a holding and stabilizing device comprising a forwardly headed rearwardly finned tubular tail piece, a plurality of forwardly projected spring fingers on the tail piece spaced radially at their bases to receive a grenade against the head of the tail piece said fingers being initially spaced at their extremities less than the medial diameter of the grenade and having claw elements thereon spaced from the tail piece to engage one of said grooves of the grenade, one of said fingers having mounted thereon a rearwardly extended arm having a lateral tongue yieldable to a predetermined pressure, a sleeve slidably thereon adapted to receive slidably therethrough the longitudinal safety lever of an engaged grenade, said sleeve being of a mass sufficient to exert by setback said predetermined pressure against said tongue and movable then from said arm to release the lever.

7. In a launcher adapted for a fragmentation grenade having a circular shell body with a plurality of circumscribing grooves therein, a holding and stabilizing device comprising a forward-

ly headed rearwardly finned tubular tail piece, a plurality of forwardly projected spring fingers on the tail piece spaced radially at their bases to receive a grenade against the head of the tail piece said fingers being internally spaced at their extremities less than the medial diameter of the grenade and having claw elements thereon spaced from the tail piece to engage one of said grooves of the grenade, one of said fingers having mounted thereon a rigid rearwardly extended arm, a sleeve slidably thereon to clear the arm and adapted to receive slidably therein the longitudinal extended safety lever of a grenade and tending to slide rearwardly from said arm and lever by setback when the adapter and grenade are launched, and releasable means to hold the sleeve in engaged position responsive to predetermined setback force in the sleeve to release the same.

8. The structure of claim 5 in which said clip support is frangible, the ends of the supporting finger and the support being apertured and riveted together and male and female inter-locking parts being formed on the respective abutting end parts.

9. The structure of claim 5 in which said clip support is frangible, the ends of the supporting finger and the support being apertured and riveted together and male and female inter-locking parts being formed on the respective abutting end parts, the major rear part of the clip support being offset from the adjacent finger part.

10. The structure of claim 5 in which said clip support is frangible, the ends of the supporting finger and the support being apertured and riveted together and male and female inter-locking parts being formed on the respective abutting end parts and having a medial knob on its under side next to finger spaced from said tongue more than the length of said sleeve, whereby when the sleeve is engaged around the knob an inserted safety lever will be clamped against the support by the outer side of the sleeve.

11. The structure of claim 5 in which said clip
